SAFETY DEVICE FOR FLATIRONS

Henry Lemo, Chicago, Ill.

Application May 18, 1932. Serial No. 611,967

17 Claims. (Cl. 68—26)

This invention relates to safety devices for flat irons, and is more particularly directed to safety devices adapted to support the iron in suspended position above the ironing board when the iron is not being used.

Electric flat irons, as are now commonly in use, cannot be left resting upon cloth or fabric, as they will quickly scorch material of this character. Further, it may be undesirable to shut off the current to the iron, since this necessitates re-heating the iron before it can be used again, which causes a considerable loss of time. It has therefore been customary to provide raised plates or grids upon which the iron is placed when it is necessary to cease the ironing operation for a short period of time. These grids are of rather substantial construction, and do not dissipate heat readily. When it is desired, therefore, to move the grid, a considerable period of time may elapse before it is cool enough to be handled.

I therefore propose to support the iron in position above the material or fabric being ironed a sufficient distance to prevent scorching of the same, and in such manner that upon again grasping the iron it is immediately released to ironing position, the support being automatically drawn up out of the way.

In the preferred form of the invention, I provide, in combination with any common type of electric flat iron having the ordinary handle supported by a handle strap secured to the upper surface of the iron, a wire frame portion surrounding the iron and supporting the same for vertical sliding movement with respect to the frame, the iron being carried by a suitable guide slidable vertically on the frame.

The frame has a vertically extending portion forming a relatively elongated bearing for receiving the guide which supports the iron. This guide is so formed as to exert a binding or shackling action with respect to the vertically extending bearing portion of the frame when the iron is in raised position, due to the weight of the iron tending to cock the guide about this portion of the frame. The frictional resistance of this cocking action is sufficient to maintain the iron in raised position suspended above the ironing board. The iron is released from its suspended position by raising the rear end thereof, such as by grasping the handle and lifting the iron slightly, and the binding of the guide is thus eliminated and the iron is then freely slidable upon the bearing portion of the frame. A suitably disposed spring draws the frame upwardly

to a position above the lower surface of the iron, and ironing operations may then be resumed.

The invention is further characterized by providing a mounting for the iron upon the frame such that the iron may be readily removed therefrom, if desired, in order to facilitate detailed and minute ironing operations.

The frame preferably is provided with an extending tongue at the rear thereof, adapted to receive a wire for supporting the cord leading to the current supply for the iron, in order to provide a greater range of movement of the iron and to prevent the cord from interfering with ironing operations.

In order that those skilled in the art may more readily understand the construction and operation of a preferred form of my invention, I will now describe the same in detail, in connection with the accompanying drawing, in which like reference numerals refer to similar parts throughout the description.

In the drawing:

Figure 1 is a perspective view of an electric flat iron provided with the safety device of the present invention;

Figure 2 is a detail perspective view of the guide which supports the iron and which is slidable upon the frame;

Figure 3 is a perspective view showing a modified form of safety device;

Figure 4 is a sectional view of the clamping means shown in Figure 3; and

Figure 5 is a partial perspective view of a further modified embodiment of the invention.

Referring now in detail to Figure 1, I have disclosed therein the flat iron 6 having the handle strap 7 secured to the upper surface thereof, as by means of the screw 8, and having the handle 9, preferably formed of wood, or other heat insulating material, carried thereby, as is well known. The handle and strap may be of any desired configuration. The iron 6 is provided with suitable projecting prongs engaging in the socket member 10 which has the cord 11 leading therefrom to a suitable source of current supply. The iron is provided with the smooth lower surface, formed by the base 12, which engages the fabric or other material during the ironing operation.

The handle 9 is supported between the upwardly extending portion of the handle-strap 7 by means of a through bolt indicated in dotted lines by the numeral 14, which extends through the handle 9 and is suitably bolted at the rear end of the iron by means of a nut 15 engaging

over the extending tongue of a protecting plate 16 carried at the rear end of the iron and forming a protection for the socket 10. While I have disclosed the handle as being secured to the strap 5 by means of a through bolt, it is obvious that any other suitable securing means may be employed.

At its forward end, the through bolt 14 is provided with a spacing member 17, which has 10 formed integral therewith the frame receiving portion 18, comprising a pair of vertical channels or passageways 19 formed therein. The provision of a through bolt for the handle is distinctly advantageous in providing an off-center support 15 for the iron at the forward end of the handle which allows the weight of the iron to cock the iron about the frame, thus providing the binding action for suspending the iron above the frame.

The pair of spaced channels receiving the frame 20 provide for non-rotatably guiding the frame in its vertical movement with respect to the iron, and thus prevent any portion of the frame from 25 engaging the heated portion of the iron.

Preferably formed integral with the spacing member 17 is an extending threaded stud portion 20, which is adapted to receive the cover member 21, the stud 20 extending through an opening 22 formed in this member. A wing bolt 23 threads over the extending end of the stud 20, and secures 25 the member 21 in abutting engagement with the frame receiving portion 18 of the spacing member 17.

A suitable wire frame, indicated at 24, is formed to surround the iron 6, and is provided with an 30 arched forward portion 25, having a pair of vertically extending bearing rods 26 extending therefrom. These rods 26 may be welded, as indicated at 27, to the center of the arched portion 25 of the frame 24, or may be formed integral 35 with the frame. For example, the rods 26 may comprise a U-shaped member having its upper portion provided with a button or cap 28 suitably secured thereto, as by means of screw 29. The central portion of the arch 25 of the frame is provided with a forwardly extending tongue 30 having an opening for receiving one end of a spring member 31, the other end of the spring 31 being secured to the inner surface of the plate member 21 by means of the screw 32.

It is to be understood that any other suitable disposition of the spring may be provided within the scope of the invention. When the iron is in raised position, the spring is inoperative, since the binding action of the iron prevents movement 45 of the same with respect to the frame. Upon release of the iron, the spring draws the frame upwardly into inoperative position.

The frame receiving portion 18 of the spacing member 17 is preferably provided with suitable cut-away portions cooperating with the inwardly extending flanges 33, preferably case-hardened, which are formed on the plate member 21 in order to secure the plate member in rigid position with respect thereto, the channels 19 formed in the frame receiving member 18 are preferably such as to provide free sliding movement of the frame rods 26 therein, so that the iron, together with the spacing block 17 and cover plate 21, may be moved vertically along the rods with little or no frictional resistance.

As shown in Figure 1, wherein the iron is in suspended position, the weight of the iron is sufficient to cock the spacing member 17 with the frame receiving portion 18, about the rods 26 so as to engage the upper flange 33 of the

plate 21 against the flats 34 formed on the surface of the rods 26 of their upper end, in order to lock this flange securely in position with respect to the rods, and to engage the lower portion of the frame receiving member 18 against the opposite surface of the rods 26. In this manner a binding or shackle action is effected, which is sufficient to hold the iron in suspended position within the frame 24, and spaced above any fabric or other material which is being ironed. Suitable flats 34' are formed at the lower ends of the rods 26 for holding the frame in raised position after it has been drawn up above the ironing surface by the spring. 80

By grasping the handle 9 of the iron and slightly rotating the same to lift the rear end thereof upwardly, the binding action of the guide or clamp 17 is removed, and the iron slides downwardly with respect to the frame 24, due to the sliding engagement of the rods 26 in the channels 19. Further, the spring member 31 serves to draw the frame 24 upwardly above the ironing surface of the base 12 of the iron 6, where it will be out of the way and will not interfere with ironing operations. 90

The rear of the frame 24, which is preferably elevated a slight distance above the horizontally extending portion of the frame, as indicated by the portion 35 thereof, is provided with an extending tongue portion 36, which may be formed 105 by looping a portion of the rear portion 35 of the frame 24 outwardly. A cord support 37 is preferably coiled, at one end about the extending portion 36 of the frame, as indicated at 38, and at its other end is provided with a hooked portion 39 for frictionally receiving a portion of the cord 11. This cord support 37 is adapted to hold the cord 11 away from the iron 6, in order to provide a greater range of movement and less interference of the cord during the ironing operation. 110

The frame 24 is preferably formed of relatively stiff wire, of a thickness such as to support the iron in position, but which is of small mass, so as to be able to dissipate heat readily. The 120 frame is light in weight, and is simply and economically constructed. Further, the manner of forming the frame is such that it may be adapted to any type of electric flat iron which is now on the market, without departing from the scope of 115 the invention.

In Figures 3 and 4 I have disclosed a modified form of safety device for flat irons, in which the strap portion 7 of the iron 6 is directly clamped to the vertically extending portion of the frame 130 by means of a clamp member 41, which is shown in more detail in Figure 4. In this modification, I have shown a frame 24', corresponding in general configuration to the frame 24 of Figure 1, which has the vertically extending portion 135 26' formed by looping the arched portion 25' of the frame in a generally U-shaped configuration, the individual parts of the frame being brought into proximity to each other to form a substantially solid vertically extending tongue 140 26'.

The clamp or guide 41 for securing the flat iron 6 to the frame 24' comprises a recessed portion 42, having the extending ears 43 formed normal thereto, which is adapted to receive the strap 7. 145 A suitably threaded extending stud 44 is preferably formed integral with the clamp 41, and a nut 45 is threaded thereon for securing the iron to the clamp. A pair of washers 46 and 47 are provided for securing a bearing surface on the 150

opposite side of the strap 7, in order to insure a rigid and substantial support for the iron.

The clamp 41 also has the substantially U-shaped extending portion 48, which is provided with inwardly extending edges 49 engaging about the vertical portion 26' of the frame 24'. It will be apparent that the clamp 41 will have vertical sliding movement with respect to the extending portion 26' of the frame 24', and that the iron, when in raised position, will exert a binding or clamping action with respect to the extending portion 26' of the frame, due to the off-center position of the weight of the iron, which will bind the clamping portion 48 about the frame in such manner as to hold the iron in suspended position. I have shown the iron in lowered position in this modification, as distinguished from the iron in suspended position as shown in Figure 1.

In Figure 5 I have shown a further modified construction, which is adapted to provide means for readily removing the iron from the frame, if such removal is desired. In this figure I have shown the frame having the arched portion 25'', which is provided at the center thereof with the extending portion 26'', corresponding to the portion 26' of Figure 3. However, the through bolt 14' of this modification, corresponding to the through bolt 14 of Figure 1, is provided with a bifurcated end having the two extending arms 50 and 51. A sliding bracket, indicated generally at 52, is mounted about the extending portion 26'' of the frame, and is adapted to have sliding movement in a vertical direction thereon. This guide or bracket 52 is provided with cut away portions adapted to receive the arms 50 and 51 of the through bolt 14' carried by the iron 6.

A suitable spring clip member 53 having the inturned end 54 suitably welded or otherwise secured to the lower end of the bracket 52, bears against the lower edge of the extending portion of the arms 50-51 to bind them securely in the cut-away portion of the bracket 52, in order to hold the iron in position with respect to the bracket 52. However, when it is desired to remove the iron, the handle surrounding the through bolt 14' is grasped, and, by drawing the iron backwardly, the arms 50 and 51 are withdrawn from the bracket 52, and the iron may then be maneuvered independently of the frame. The arms 50 and 51 serve to provide the cocking action necessary in order to suspend the iron in raised position above the frame when it is desired to cease the ironing operation. A suitable extending tongue 55 is mounted at the upper end of the vertically extending portion 26'' of the frame, as by means of the nut 56 threaded upon an extending stud 57 formed on the frame, so that the frame may be held during removal or insertion of the iron into the bracket 52.

It will be apparent that when the iron is in raised position, the edges of the extending arms 50 and 51 will produce a cocking action on the bracket 52, tending to rotate the bracket about a horizontal axis with respect to the upwardly extending portion 26'' of the frame. This cocking action will serve to hold the iron in suspended position. By raising the iron slightly, and drawing upwardly on the tongue 55, the frame may be raised up above the iron in order to operate the iron.

It is obvious that the frame shown in either Figure 3 or Figure 5 may be provided with the extending tail portion 36, as shown in connection with the frame 24 of Figure 1, in order to pro-

vide a support for the cord receiving member 37.

The extending lug 55 of the safety device shown in Figure 5 is adapted to be grasped to raise the frame above the lower surface 12 of the iron, in order to facilitate ironing operations. However, it is obvious that in the embodiments of both Figures 3 and 5, a suitable spring member could be provided to raise the frame upwardly when the iron is released from its suspended position.

It is therefore apparent that I have provided a safety device for an iron which will maintain the iron in suspended position above the material being ironed, and which may be constructed of economical material, and is relatively light in weight and of great heat dissipating characteristics. The iron may be released from its suspended position by merely grasping the same, whereupon the binding action produced by the weight of the iron is released, and the frame may be automatically drawn up to a position out of the way by means of a spring, or may be raised upwardly by providing a suitable handle or other means for drawing the same upwardly.

I do not intend to be limited to the exact details shown and described in connection with the illustrated embodiment of my invention, but only insofar as defined by the scope and spirit of the appended claims.

I claim:

1. In combination, a frame having a vertically extending integral bearing portion, a guide engaging about and having sliding movement with respect to said bearing portion, said guide being non-rotatable with respect to said bearing portion, and a flat iron carried by said guide and adapted to provide a binding action of said guide upon said bearing portion when said iron is in raised position to maintain said iron suspended

2. In combination, a frame having a vertically extending bearing portion, notches formed at the upper end of said bearing portion, a guide engaging about and having sliding movement with respect to said bearing portion, and a flat iron carried by said guide and adapted to provide a binding action of said guide upon said bearing portion and to engage said guide in said notches when said iron is in raised position, said iron being removably mounted on said guide.

3. In a safety device for a flat iron having a laterally extending handle, a frame surrounding said iron and formed of relatively rigid wire, said frame having a vertically extending bearing portion, guide means freely slidable upon said bearing portion, means comprising a through bolt extending through said handle for securing said iron to said guide means to dispose the weight of said iron away from said guide means, said guide means being cramped against movement with respect to said bearing portion when said iron is in suspended position.

4. In a safety device for a flat iron having a laterally extending handle, a frame having a vertically extending bearing portion, a guide slidable upon said bearing portion and having channels formed therein for receiving said bearing portion, a cover member clamped over said channel portion of said guide, and clamping means comprising a through bolt extending through the handle of said iron and carried by said guide for supporting said iron at the forward end thereof.

5. A safety device for flat irons, comprising a wire frame formed with parallel-extending horizontal side portions, said frame having an arched forward portion adapted to extend over and above the toe of said iron, a raised rear portion

- extending beyond the heel of said iron, and an integral vertical portion comprising integral post portions extending from said arched forward portion and forming a bearing for slidably and 5 non-rotatably supporting said iron in raised position within said frame.
6. A safety device for electric flat irons, comprising a wire frame formed with parallel-extending horizontal side portions, said frame having an arched forward portion adapted to extend over the toe of said iron, a raised rear portion extending beyond the heel of said iron, an extending tongue formed on said rear portion and adapted to receive a cord supporting member, 10 and a vertical portion extending from said arched forward portion and forming a bearing for slidably supporting said iron.
7. In combination, a frame formed of wire and having a vertically extending forward portion, 20 a flat iron having a conducting means extending therefrom leading to a source of supply for heating said iron, a handle carried by said iron, a through bolt securing said handle to said iron, said through bolt having a spacing portion at the front thereof adapted to engage the vertically extending portion of said frame, a cover member secured over said spacing portion and forming a guide freely slidable on said vertically extending portion of said frame, and a supporting member carried at the rear of said frame for engaging the conducting means extending from said iron. 25
8. A safety device for a flat iron comprising a supporting frame having a vertically extending bearing portion at one end thereof, and guide means supporting said iron upon said frame, said guide means being slidable on said bearing portion and non-rotatable with respect thereto.
9. A safety device for flat irons comprising a frame having a vertically extending bearing portion at one end thereof, said bearing portion comprising spaced post members, and guide means slidably mounted on said bearing portion for non-rotatably supporting a flat iron for vertical movement within said frame the weight of said iron when supported by said frame binding said guide means about said bearing portion. 40
10. A safety device for flat irons comprising a frame having an arched forward portion, posts extending vertically from said arched portion, means for spacing said posts laterally at the top and bottom thereof, and iron-supporting guide means slidable on and having shackling engagement with said posts. 50
11. A safety device for flat irons comprising a frame having an arched forward portion, posts extending vertically from said arched portion, means at the bottom of said posts for holding said posts in spaced relation, means at the upper end of said posts for holding said posts in spaced relation, and guide means supporting a flat iron for vertical movement within said frame and slidable on said posts, said guide means having binding engagement with said posts when in 65 raised position.
12. A safety device for a flat iron having a horizontal handle comprising a frame having a vertically extending bearing portion at the forward end thereof, guide means slidable on said bearing portion, and a through bolt extending rearwardly from said guide means through the handle of said iron for securing said iron to said guide means. 80
13. A safety device for a flat iron comprising a frame having a vertically extending bearing portion, notch means formed in said bearing portion adjacent the upper end thereof, and a guide slideable on said bearing portion and having means for supporting said iron, said guide having means engaging in said notched means when said guide is in raised position. 85
14. A safety device for a flat iron comprising a frame having a vertically extending bearing portion, notch means formed in said bearing portion, a guide slidably mounted on said bearing portion and having means for supporting said iron, and means carried by said guide means engaging in said notch means when said iron is in raised position to support said iron above said frame. 90
15. A safety device for a flat iron comprising a frame having a vertically extending bearing portion disposed within the peripheral extent of said iron, guide means secured to said iron and receiving said bearing portion, said frame being 105 slideable with respect to said guide means from iron supporting position below the surface of said iron to a position above said surface, said guide means having binding engagement with said bearing portion when said frame is in iron supporting position. 100
16. In a flat iron having a forwardly extending toe portion, a safety device therefor comprising a frame having its forward portion arched over the toe portion of said iron, a vertical bearing portion extending from said arched portion, and guide means slidable on said bearing portion and providing for movement of said frame from a position below the surface of said iron to a position above said surface, said guide means 115 supporting said iron whereby the weight of said iron binds said guide means about the bearing portion when said frame is in lowermost position. 120
17. In a flat iron having a forwardly extending toe portion and a handle portion, a safety device therefor comprising a frame having its forward portion arched over the toe portion of said iron, a vertical bearing portion extending centrally from said arched portion, and guide means projecting forwardly of the handle portion of 130 said iron and disposed above the toe portion thereof within the peripheral extent of said toe portion, said guide means receiving said vertical bearing portion of said frame and providing for movement of said frame from a position below 135 the lower surface of said iron to a position above said surface. 125
